FIG. 3. Inventor:
Mahlon W. Kenney
By: Cox x Moore atty

UNITED STATES PATENT OFFICE

2,087,257

REFRIGERATOR CABINET

Mahlon W. Kenney, Chicago, Ill., assignor, by
mesne assignments, to Reconstruction Finance
Corporation, Chicago, Ill., a corporation

Application July 7, 1934, Serial No. 734,078

9 Claims. (Cl. 62—116)

My invention relates in general to refrigeration and has more particular reference to a mechanical refrigerating system particularly well adapted for domestic use.

One of the important objects of the invention is to provide for cooling the operating parts of the refrigerating system, by natural draft.

Another important object resides in providing a mechanical refrigerating system assembled in a cabinet for use as a domestic refrigerator wherein means is provided for utilizing convection currents caused by the generation of heat in certain parts of the refrigerating system to cause a natural draft of air to circulate in the vicinity of the heat-developing parts for the purpose of cooling the same.

Another important object is to provide a refrigerator cabinet formed to receive the elements of a mechanical refrigerating system including parts in which heat is liberated during the operation of the system and in so forming the cabinet as to provide a passage in connection with said heat-generating parts whereby convection currents of relatively cold air are set up in said channel in heat-exchange relationship with said parts.

Another important object is to provide a refrigerator cabinet containing mechanical refrigerating means, said cabinet having a duct or flue in which heat-liberating elements of the refrigerating system are disposed in position to cause a draft of relatively cold air to circulate in the flue for the purpose of carrying off heat liberated by said elements.

Another important object is to provide a refrigerator cabinet having a cooling chamber and a mechanism chamber below the cooling chamber and having a mechanical refrigerating system including a cooling device in the cooling chamber, and devices, including mechanical means adapted to liberate heat as a result of the operation of the system, said devices being located in the mechanism chamber, and said cabinet having means forming a flue extending in said mechanism chamber and behind said cooling chamber and cooperatively associated with said heat-generating elements, whereby to utilize a natural draft through said flue for the purpose of abstracting heat from the heat-generating elements.

Another important object is to provide a mechanical refrigerating system including a refrigerant compressor and condenser wherein the compressor is located above the condenser in the position to be cooled by rising air currents drawn

through the condenser as a result of heat liberated by the condenser.

Another important object is to provide a mechanical refrigerating system including a refrigerant condenser and compressor wherein the condenser is mounted horizontally so as to create a natural draft of cooling air through the condenser by convection and wherein the compressor is located above the condenser in the path of said draft.

These and numerous other objects, advantages and inherent functions of the invention will become apparent as the same is more fully understood from the following description, which, taken in connection with the accompanying drawing discloses a refrigerator embodying my present invention.

Referring to the drawing,

Figure 1 is a perspective view illustrating a refrigerating system as assembled in a cabinet to provide a domestic refrigerator embodying my present invention;

Figure 2 is a side view partially sectionalized of the device shown in Figure 1;

Figure 3 is a sectional view taken substantially along the line 3—3 in Figure 2; and

Figure 4 is a perspective view showing a demountable portion of the refrigerating system.

To illustrate the invention I have shown on the drawing a mechanical refrigerating system assembled in a cabinet 11 adapted for use as a domestic refrigerator although it will be obvious that the refrigerating system need not necessarily be arranged in a cabinet.

The refrigerating system comprises a cooling device 13, associated heat-liberating elements wherein heat is liberated during the operation of the refrigerating system, and means co-operating with the heat-liberating elements of the system whereby the same are cooled by natural drafts of cold air set up by the liberation of heat by said elements during the operation of the system.

In the illustrated embodiment, the cooling device 13 comprises an evaporator in which a suitable refrigerating medium such as dichloromethane in liquid condition is evaporated for the absorption of heat, while the heat-liberating elements include a compressor 15 and a condenser 17, the compressor being operatively connected to receive the evaporated refrigerant, compress the same, and deliver the compressed refrigerant to the condenser in which the same is liquefied, the condenser, in turn, being connected to deliver

the refrigerant in liquid condition to the evaporator.

The condenser comprises a plurality of pipe coils 19 arranged in serpentine or other suitable fashion, the pipe coils being finned, if desired, to increase their heat-exchanging capacity. Heat is liberated from the gaseous refrigerant at the condenser in order to liquefy the same, and the condenser is preferably arranged in substantially 10 horizontal position so that the heat liberated in the coils thereof will cause an upward circulation of air by natural draft through the condenser coils so that the cold air will be continuously drawn through the condenser for the purpose of continuously exposing the gasified refrigerant, and normally operates at a relatively higher temperature than the air passing through the condenser.

In order to maintain the compressor at a safe 20 operating temperature, I dispose the same in the path of the ascending air currents passing the condenser so that the air draft initiated through the condenser by the fact that its coils are relatively warm, but which air is but slightly heated 25 in passing through the condenser, may also be utilized to cool the compressor. The compressor may, of course, be of any suitable form, but I prefer to enclose it in a casing having upwardly extending fins 21 disposed in planes extending in 30 the direction of the air-flow through the condenser in order to increase the heat-exchanging surface of the compressor casing. I also prefer to drive the compressor by means of a prime mover, preferably an electric motor housed within 35 the compressor casing so that the compressor and its prime mover comprise a motor compressor unit sealed within the finned casing.

As heretofore stated, I prefer to assemble the 40 elements of the refrigerating system in the cabinet 11. To this end the cabinet is formed with an upper refrigerating compartment 23, and the cooling element 13 is disposed in the cabinet in heat-exchange relationship with respect to the atmosphere within the chamber 23. Preferably 45 the element 13 is mounted directly within the chamber although obviously it may be disposed in an auxiliary chamber in the cabinet and communicating with the refrigerating chamber 23 to set up air circulation between the auxiliary chamber 50 and the refrigerating chamber. The cabinet 11 also preferably is formed with a mechanism compartment 25 disposed in the cabinet below the refrigerating chamber, the compressor and condenser being mounted in the mechanism compartment. The walls of the cabinet 11 are also 55 preferably formed with built in conduits 27 and 29, the conduit 27 being connected with the unit 13 and with the compressor to form a means through which the gasified refrigerant from the evaporator may be drawn into the suction port 60 of the compressor. The conduit 29 is connected with the condenser and with the evaporator to form means through which the liquefied refrigerant may be delivered from the condenser to the evaporator. The conduits 27 and 29 extend into 65 the mechanism compartment for connection respectively with the compressor and condenser, the conduit 27 being connected directly with the compressor intake port while the conduit 29 is 70 connected with the outlet of an expansion valve 31, preferably of the float-controlled type. The float-controlled expansion valve, in turn, is connected preferably through a dehydrator 33 with the condenser outlet. The compressor has a 75 charge which is connected directly with the con-

denser inlet by means of a conduit 35 preferably extending entirely within the mechanism compartment 25. The cabinet 11 also is provided with means forming a flue 37, the lower portions of which extend within the mechanism compartment and enclose the sides of the condenser and compressor in order to assist in creating the cooling draft of air through the condenser and past the compressor. The upper portions of the flue 37 extend at the rear of the cabinet, the flue passing behind the refrigerating compartment 23 and terminating preferably slightly below the top of the cabinet. The condenser, float-controlled expansion valve, dehydrator and compressor are preferably mounted in any suitable or preferred 10 fashion on a support panel 39 whereby all of the parts of the system which are located in the mechanism compartment may be assembled in the cabinet as a unit. The condenser coils are preferably arranged in a frame 41 which is 15 mounted on the support panel 39 opposite an opening 43 of said panel to permit the air drafts circulating through the condenser to rise upwardly through said opening 43 before traversing the condenser coils. The cabinet also is preferably 20 mounted on suitable supporting legs 45 in order to permit an unrestricted flow of air to and through the opening 43, the condenser and the flue. The condenser coils also are preferably arranged in a plane sloping downwardly from the 25 inlet side of the condenser coils to the outlet side, which is disposed preferably in the rearmost portions of the mechanism compartment. The compressor is preferably mounted in the rearmost 30 portions of the compartment above that part of the condenser which is adjacent the condenser outlet, since the lower temperature prevails in the condenser coils adjacent the condenser outlet for the reason that the refrigerating medium, by the 35 time it approaches the condenser outlet, has been cooled and liquefied during its passage through the condenser coils adjacent the condenser inlet. The upper portions of the flue 37 are preferably 40 permanently mounted to the cabinet. The lower portions of the flue, however, may be supported on the panel 39 and may be removed from the cabinet with the mechanism carried by said panel. To this end the lower flue portions 45 comprise walls having edges 47 and 49 formed for cooperation with the lower edges of the flue 50 portions permanently mounted on the cabinet so that when the panel 39 and the mechanism thereon is assembled in the compartment 25, the lower flue portions will be positioned in cooperative alignment with the upper flue portions to 55 form a continuous flue opening at its lower end at the bottom of the cabinet, and at its upper end at the top of the cabinet and providing passage through which currents of cooling air may pass in heat-exchange relationship with respect 60 to the heat-generating elements 15 and 17. The panel 43 may also carry a housing 51 containing electrical connections for applying power to the compressor driving motor from an external power source. In the illustrated embodiment, 65 electrical power is delivered to the electrical system within the casing 51 through a cable 53 provided with a plug 55 adapted for detachable connection in an electrical power outlet of ordinary construction whereby electrical power, such 70 as is ordinarily available in house lighting systems, may be utilized for driving the compressor. The power distribution system contained within the casing 51 is connected by means of a cable 75 with a compressor motor and is also connected 75

by means of a cable 59 with a thermostat located in heat-exchange relationship with respect to the cooling device 13 in order that the operation of the compressor may be controlled in response to temperature conditions prevailing in the vicinity of the cooling device.

The conduits 27 and 29 at one end are provided for detachable connection with the cooling unit in order that the cooling unit may be removed from the system for repair or replacement without disturbing the conduits 27 and 29, which are built into the walls of the cabinet. The conduits 27 and 29 also are provided for detachable connection respectively with the compressor, and 15 the expansion valve 31 in order to permit the removal from the cabinet of the compressor, condenser and other mechanism carried by the panel 39 without disturbing said conduits.

It is thought that the invention and numerous 20 of its attendant advantages and inherent functions will be understood from the foregoing description, and it is obvious that numerous changes may be made in the form, construction and arrangement of the several parts without departing from the spirit or scope of my invention, or sacrificing any of its attendant advantages, the form herein described being a preferred embodiment for the purpose of illustrating the invention.

Having thus described my invention, what I 25 claim as new and desire to secure by Letters Patent is:

1. A refrigerator comprising a cabinet forming a refrigerating chamber, a mechanism compartment under the refrigerating chamber, a flue having an end in said mechanism compartment and extending from and upwardly of said mechanism compartment and opening above said mechanism compartment, said system comprising a heat absorbing device in heat-exchange relationship with the atmosphere within the refrigerating chamber, and a heat-liberating device located in the mouth of said flue in the mechanism compartment to create a natural air draft through said flue and in heat-exchange relationship with respect to the heat liberating device for the purpose of cooling the same.

2. A refrigerator comprising a cabinet forming a refrigerating chamber, a mechanism compartment under the refrigerating chamber, a flue having an end in said mechanism compartment and extending from and upwardly of said mechanism compartment and opening above said mechanism compartment, said system comprising a heat absorbing device in heat-exchange relationship with the atmosphere within the refrigerating chamber, and a heat-liberating device located in position in the flue to create a natural air draft through said flue and in heat-exchange relationship with respect to the heat liberating device for the purpose of cooling the same, said flue having a portion extending within the mechanism chamber and opening in the bottom of the cabinet below the heat liberating element.

3. A refrigerator comprising a cabinet forming a refrigerating chamber, a mechanism compartment under the refrigerating chamber, a flue having an end in said mechanism compartment and extending from and upwardly of said mechanism compartment and opening above said mechanism compartment, said system comprising a heat absorbing device in heat-exchange relationship with the atmosphere within the refrigerating chamber, a compressor in said flue,

and a heat-liberating condenser located in position in the mouth of the flue to create a natural air draft through said flue and in heat-exchange relationship with respect to the compressor as well as the heat-liberating condenser 5 for the purpose of cooling the same, said flue extending from the mechanism chamber upwardly in the cabinet rearwardly of the refrigerating compartment, and having an upper open end at the top of the cabinet.

4. A refrigerator comprising a cabinet having a cooling chamber, a mechanism compartment under the cooling chamber, means forming a flue having lower portions extending in said mechanism compartment and upper portions extending 10 from the mechanism compartment upwardly adjacent a side of the cooling chamber, a refrigerating system in said cabinet comprising a heat-absorption device mounted in said refrigerating chamber, a heat-liberating device in the mechanism compartment and co-operatively associated 15 with said flue in position to initiate a natural air draft through said flue in heat-exchange relationship with said device whereby to cool the same, and conduit means in the walls of said cabinet 20 for connecting the absorption element with the heat-liberating device, said heat-liberating device being removably mounted in said mechanism compartment and said conduit means being formed for detachable connection with said 25 heat-liberating device whereby the same may be assembled in and removed from the mechanism compartment without disturbing the mounting of said conduit means, portions of said flue-forming means being connected to the heat-liberating device for removal and insertion with said device and formed to co-operate with other portions of the flue-forming means permanently mounted in the cabinet whereby to form a complete flue when the heat-absorbing device is in 30 operating position in the mechanism compartment.

5. A refrigerator comprising a cabinet having a cooling chamber, a mechanism compartment under the cooling chamber, means forming a flue having lower portions extending in said mechanism compartment and upper portions extending 35 from the mechanism compartment upwardly adjacent a side of the refrigerating chamber, a refrigerating system in said cabinet comprising a heat-absorption device mounted in said refrigerating chamber, heat-liberating devices including a compressor and a refrigerant condenser located in the mechanism compartment, a heat-liberating device in the mechanism compartment 40 and co-operatively associated with said flue in position to initiate a natural air draft through said flue in heat-exchange relationship with the condenser and compressor when the system is in 45 operation for the purpose of cooling the same, and conduit means in the walls of said cabinet for connecting the absorption element, the condenser and compressor in a refrigerant circulating system, portions of the flue-forming means, said compressor and condenser being carried on a 50 panel removably mounted in said mechanism compartment, said conduit means being formed for detachable connection with the condenser and compressor whereby the same may be assembled 55 and removed from the mechanism compartment without disturbing the mounting of said conduit means, and the portions of the flue-forming means carried by said removable panel being formed for co-operation with other portions of the flue-forming means permanently arranged in the cabinet 60

whereby to form a complete flue when the panel is positioned in the compartment.

6. A refrigerator comprising a cabinet having a cooling chamber, a mechanism compartment under the cooling chamber, means forming a flue having lower portions extending in said mechanism compartment and upper portions extending from the mechanism compartment upwardly adjacent a side of the refrigerating chamber, a refrigerating system in said cabinet comprising a heat-absorption device mounted in said refrigerating chamber, heat-liberating devices including a condenser and a compressor in said mechanism compartment in position to initiate a natural air draft through said flue during the operation of the system, and conduit means mounted in said cabinet and operatively connecting the absorption element, the condenser and the compressor in a refrigerant circulating system, said condenser and compressor being carried on a support panel removably mounted in the mechanism compartment, said panel when positioned in the cabinet forming the bottom wall of the mechanism compartment and being formed with an opening, said condenser being mounted on the panel opposite said opening, and the compressor being supported on said panel above said condenser, portions of said flue-forming means being also carried by said panel in the compartment, said conduit means being formed for detachable connection with the condenser and compressor and said portions of the flue-forming means carried by the panel being adapted when the panel is positioned in the cabinet to co-operate with other portions of the flue-forming means which are permanently located in the cabinet whereby said condenser, compressor and portions of the flue-forming means are mountable in and removable from the cabinet as an assembly unit.
7. A refrigerator comprising a cabinet forming a refrigerating chamber, a mechanism compartment under the refrigerating chamber, a flue having an end in said mechanism compartment and extending from and upwardly of said mechanism compartment and opening above said mechanism compartment, said system comprising a heat absorbing device in heat-exchange relationship with the atmosphere within the refrigerating chamber, and a heat-liberating device located in the mouth of said flue in the mechanism compartment to create a natural air draft through said flue and in heat-exchange relationship with respect to the heat-liberating device for the purpose of cooling the same, and conduit means in the walls of said cabinet for connecting the absorption element

with the heat-liberating device, said heat-liberating device being removably mounted in said mechanism compartment and said conduit means being formed for detachable connection with the heat-liberating device whereby the same may be assembled in and removed from the mechanism compartment without disturbing the mounting of said conduit means.

8. A refrigerator comprising a cabinet forming a refrigerating chamber, a mechanism compartment under the refrigerating chamber, a flue having an end in said mechanism compartment and extending from and upwardly of said mechanism compartment and opening above said mechanism compartment, said system comprising a heat absorbing device in heat-exchange relationship with the atmosphere within the refrigerating chamber, and a heat-liberating device located in the mouth of said flue in the mechanism compartment to create a natural air draft through said flue and in heat-exchange relationship with respect to the heat-liberating device for the purpose of cooling the same, said heat-liberating device being removably mounted in said mechanism compartment and portions of said flue-forming means being connected with the heat-liberating device for removal and insertion in the cabinet with said device and formed for co-operation with permanently mounted portions of the flue whereby to form a complete flue when the heat-liberating device is in operating position.

9. A refrigerator comprising a cabinet forming a refrigerating chamber, a mechanism compartment under the refrigerating chamber, a flue having an end in said mechanism compartment and extending from and upwardly of said mechanism compartment and opening above said mechanism compartment, said system comprising a heat absorbing device in heat-exchange relationship with the atmosphere within the refrigerating chamber, and a heat-liberating device located in the mouth of said flue in the mechanism compartment to create a natural air draft through said flue and in heat-exchange relationship with respect to the heat-liberating device for the purpose of cooling the same, said cabinet comprising a removable portion carrying the heat-liberating device within the mechanism compartment and a part of the flue in position such that when the removable cabinet portion is assembled, the flue portions carried thereby are positioned to co-operate with other flue portions permanently mounted on the cabinet.

MAHLON W. KENNEY.
